P. H. CAPPER & L. F. McCREARY,
COMBINATION BINDING POST.
APPLICATION FILED AUG. 9, 1911.

Patented Apr. 23, 1912.

Fig. 1.

UNITED STATES PATENT OFFICE.

PHILLIP H. CAPPER AND LOUIS F. MCCREARY, OF PITTSBURGH, PENNSYLVANIA.

COMBINATION BINDING-POST.

1,024,248.

Specification of Letters Patent. Patented Apr. 23, 1912.

Application filed August 9, 1911. Serial No. 643,173.

To all whom it may concern:

Be it known that we, (1) PHILLIP H. CAPPER and (2) LOUIS F. MCCREARY, citizens of the United States of America, residing at Pittsburgh, in the county of Allegheny and State of Pennsylvania, have invented certain new and useful Improvements in Combination Binding-Posts, of which the following is a specification, reference being had therein to the accompanying drawing.

This invention relates to a combination binding post particularly designed for terminal heads in electrical construction, such 15 for instance, as cable boxes.

The primary object of our invention is the provision of positive and reliable means, in a manner as will be hereinafter set forth, for connecting the wires upon one side of the 20 terminal head to those upon the opposite side, the connection being of such form that it will withstand jarring and vibration and save time and money in the construction of new terminal heads and the repairing and 25 testing of those already in use.

A further object of our invention is to furnish a binding post with permanent wire holders or clips that reduces the resistance in a line to a minimum and assures a ready 30 and convenient means of connecting wires of branch circuits.

Terminal heads are constantly subjected to jars and vibrations in many places which loosen the nuts on binding posts now in use, 35 causing poor connections, increases the line resistance and in many instances it is necessary to install new wires and these new wires are greatly weakened on account of the bending which is now necessary to make 40 the connections. Furthermore, in testing out a cable it is often found that loose connections are on the inside of the terminal head, and in order to repair the damage, it is necessary to take off the front plate which is 45 held by a number of screws, consequently considerable time and labor is consumed. Still further, in the present type of binding post it is necessary to wrap the wires around the screws, thereby weakening the 50 wire and causing breaks that interfere with the successful operation of the terminal head, particularly in a cable box.

We obviate the above defects by a binding post that can be advantageously used in 55 connection with the cable box, the inner terminals being made permanent whereby it

will be unnecessary to open the cable box, particularly when the wire trouble can be easily observed upon the exterior thereof.

The invention will be hereinafter specifically described and then claimed, and reference will now be had to the drawing, where- 60 in:

Figure 1 is a perspective view of a portion of the cable box provided with a combination binding post in accordance with this invention. Fig. 2 is a side elevation of the binding post. Fig. 3 is a vertical sectional view of the same. Fig. 4 is an enlarged side elevation of a modified form of post, and 70 Fig. 5 is a longitudinal sectional view of a modified form of binding post.

A post in accordance with this invention comprises a bolt 1 having one end thereof screw threaded, as at 2 and the opposite end thereof provided with an integral head 3, said head being removed from the extreme end of the bolt 1, whereby the extremity can be provided with flat faces 4 and with a transverse opening 5. The opening 5 is adapted to receive the end of a wire or an electric conductor 6 and to retain the end of a wire in engagement with the post, a C-shaped clamping member or clip 7 is employed. In the preferred form of construction, the clip has one end thereof integral with the head 3 and the opposite end is longitudinally slotted, as at 8 and bent to form a finger grip 9. The slot 8 provides clearance for the lower end of the bolt 1 and said clip is depressed or shifted toward 90 the head 3, whereby the end of the wire 6 can be inserted in the opening 5. Then by releasing the clip, the resiliency thereof is adapted to hold the clip in engagement with the wire and retain the wire in engagement with the lower wall of the opening 5. In this manner the wire is detachably held, yet a positive connection is made between the wire, clip and bolt. The head 3 and the clip 7 constitute an inner terminal that maintains a connection under the most trying circumstances, thereby obviating an examination of the inner terminals, particularly when used in connection with a cable 100 box 10.

As illustrated in Figs. 1 to 3 inclusive, the bolt 1 extends through insulations 11 arranged in the wall 12 of the cable box, and detachably mounted upon the upper screw 110 threaded end of the bolt 1 is a nut 13 having an integral clip or clamping member 14

similar to the clip or member 7. The nut 13 has a stem 15 with flat faces and with transverse openings 16 and 17, said stem representing a continuation of the bolt 1. 5 The wire 18 is adapted to be retained in the opening 16 by the clip or clamping member 14, and when it is desired to insure a more positive connection, the end of the wire 18 can be bent and carried into the opening 17. 10 It is unnecessary to wind the end of the wire around the stem 15, as the manner in which the wire is connected to said stem insures a positive connection. After the nut 13 has been positioned upon the bolt 1 and the wire 15 15 connected to the stem 15 by the clip or member 14, the nut 13 cannot rotate on account of the side walls of the slot of the clip engaging the flat sides of the stem 15, consequently the nut 13 cannot become accidentally 20 displayed and serve functionally as though it were a permanent part of the post. It assures an easy path for the flow of an electric current and eliminates the resistance of the connection which heretofore 25 has caused considerable trouble. The nut 13 is rectangular for the convenience of loosening and tightening the binding post.

In Fig. 4 of the drawing there is illustrated a modification of the invention, 30 wherein the clip or clamping member 19 is made detachable and is held between the head 3 and a washer 20.

The modification illustrated in Fig. 5 consists of two clips 21 and 22, the clip 22 being 35 arranged within the clip 21. The clip 22 has a tongue 23 extending into the slots 24 and 25 of the clips 22 and 21 respectively. This tongue is adapted to hold a wire 26 between the clips 21 and 22, and to bind the 40 clips together upon the wire 26, a pin 27 is inserted between the tongue 23 and the clip 25. In lieu of the pin 27, the end of the wire can be bent to pass between the clip 22 and the tongue 23. The advantage of this

construction is that a positive connection is 45 made between the wire 26 at more than one point and the danger of leakage is removed.

From the foregoing it will be observed that the binding post comprises two parts that can be easily and quickly assembled to 50 provide terminals or fasteners for the ends of wires, and with the clips or clamping members made of light and durable resilient metal, a strong spring pressure can be obtained for positively establishing a connection 55 between the ends of the wires and the binding post.

Our invention is not limited to the details of construction, and such changes as fall within the scope of the appended claims can 60 be resorted to without departing from the spirit of the invention.

What we claim is:—

1. In a binding post, a bolt, a resilient clip formed integral with one end of said bolt and adapted to retain a wire in engagement with said bolt, a nut screwed upon the opposite end of said bolt, a stem carried by said nut, and a resilient clip formed integral with said nut and adapted to retain a wire 70 in engagement with said stem.

2. In a combination binding post, a bolt, a head carried by one end of said bolt, a resilient clip formed integral with said head and adapted to retain a wire in engagement 75 with said bolt, a nut screwed upon the opposite end of said bolt, a stem carried by said nut, and a resilient clip formed integral with said nut and adapted to retain a wire in engagement with said stem. 80

In testimony whereof we affix our signatures in the presence of two witnesses.

PHILLIP H. CAPPER.
LOUIS F. McCREARY.
